UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

FEEDER FOR INGOT MOLDS.

Application filed February 8, 1924. Serial No. 691,737.

To all whom it may concern:

Be it known that BLOOMFIELD H. HOWARD and ERNEST J. TURNER, citizens of the United States, residing, respectively, at 5 Washington, District of Columbia, and Pittsburgh, in the county of Allegheny and State of Pennsylvania, have invented certain new and useful Improvements in Feeders for Ingot Molds, of which the following is 10 a specification.

Our invention relates to improvements in reversible hot top feeders for ingot molds.

The object of our invention is to provide a feeder for ingot molds adapted to be supported on the upper end of the mold and at 15 the same time provide a feeder which will prevent the formation of what is known as "piping" and at the same time reduce segregation.

Another object of our invention is to provide a reversible feeder adapted to fit molds having bores of different diameters and at 20 the same time providing means whereby the feeder is rigidly supported so that it will 25 have no lateral movement during the pouring operation.

Another object of our invention is to provide a reversible feeder whereby ingots of 30 different lengths may be cast in the same ingot mold.

A further object of our invention is to provide a reversible feeder of this character in which the feeder is rigidly held in the mold in either position and so constructed 35 that when in one position in the mold it extends a greater distance into the mold than when reversed.

A still further object of our invention is to provide a simple, cheap and effective 40 feeder having certain details of structure and combination of parts hereinafter more fully set forth.

In the accompanying drawings:—

Figure 1 is a perspective view of a mold 45 showing our improved feeder.

Figure 2 is a vertical transverse sectional view of Figure 1.

Figure 3 is a transverse sectional view similar to Figure 2 showing the feeder in 50 the reversed position.

Figure 4 is a top plan view of a sectional feeder showing a modified form of supporting rib.

Figure 5 is a vertical transverse sectional 55 view of Figure 4.

Figure 6 is a top plan view of a modified form of sectional feeder showing the form of supporting ribs shown in Figures 1, 2 and 3.

Figure 7 is a vertical transverse sectional view of Figure 6.

Referring now to the drawings, 1 represents the mold and 2 the feeder. While we have shown the square feeder and a correspondingly shaped mold it will be understood that the same could be round, square, 65 rectangular or any desired shape without departing from our invention.

In Figure 1 of the drawings we have shown the four walls of the square feeder 70 2 with outwardly extending ribs 3. These ribs 3 as shown are arranged intermediate the upper and lower ends 4 and 5 of the feeder. The outer face of the ribs 3 is beveled from a central line downwardly as 75 indicated at 6 and upwardly as indicated at 7 and whereby they enter the bore of the mold and tightly wedge the feeder in the upper end of the mold to prevent any lateral movement in the mold during the pouring 80 operation. This beveled outer wall of the ribs 3 allows the application of the feeder to molds in which the bore varies and yet at all times causing a wedging action to firmly hold the feeder in the mold. By reversing 85 the feeder in the mold as shown in Figure 3 of the drawings, the wedging action is precisely the same.

In Figure 4 of the drawings, we have shown a rectangular feeder composed of four 90 sections 8, 9, 10 and 11 said sections carrying ribs 13, 14, 15 and 16 each rib having a tapering wall 17 terminating in a horizontal flat wall 18. The ribs 17 as shown like those shown in Figures 1, 2 and 3 are arranged intermediate the ends of the feeder and whereby the reversal of the feeder in the mold allows the feeder to extend a greater or less distance into the mold. The tapered walls 17 also allow the feeder to be applied to 100 molds having bores of greater diameters and is used in this manner especially wherein the bore of the mold is greater than the diameter of the feeder.

In Figure 6 we have shown a sectional 105 feeder made of four sections 19, 20, 21 and 22 each section carrying a rib 23, 24, 25 and 26 a rib being arranged on the wall of each section intermediate its ends and having the beveled walls 27, and 28 extending towards 110

its upper and lower ends. By this arrangement it will be seen that the feeder is reversible and locked in the mold in either of its positions by the beveled walls 27 and 28.

5 In the structure shown in Figures 4, 5, 6 and 7 we have provided a sectional feeder in which the section can be tightly held in this operative position when the bore of the mold is of the same diameter as the exterior diameter of the feeder or can be firmly locked together when the bore of the mold is of a greater diameter than the feeder. While we have shown and described these specific arrangements of the ribs it will be understood that two or more ribs can be arranged on each side wall of the feeder or arranged in any desired manner without departing from our invention or an annular flange arranged around the feeder and beveled toward the upper and lower ends.

Having thus full described our invention what we claim is:—

25 1. A reversible feeder for ingot molds comprising a body portion, ribs carried by the outer periphery of the feeder and having a tapering outer face.

30 2. A reversible feeder for ingot molds comprising a body portion, and tapering ribs carried by the body portion intermediate its upper and lower ends.

35 3. A reversible feeder for ingot molds comprising a body portion, and ribs carried by the outer periphery of the body portion and tapered in both directions.

40 4. A reversible feeder for ingot molds comprising a body portion, ribs carried by the outer periphery of the body portion intermediate its ends and tapered in two directions.

45 5. A reversible feeder for ingot molds

comprising a body portion formed of a series of sections and tapering ribs carried by each section.

6. A reversible feeder for ingot molds comprising a body portion formed of a series of vertical sections and tapering ribs carried by each section intermediate their ends.

7. A reversible feeder for ingot molds comprising a body portion formed of a series of sections each section having ribs intermediate their ends and tapering in both directions.

8. A reversible feeder for ingot molds comprising a body portion formed of a series of vertical sections each section having ribs intermediate their upper and lower ends and having a tapering wall.

9. A reversible feeder for ingot molds comprising a body portion having tapering ribs on its outer walls, said ribs arranged nearer one end than the other.

10. A reversible feeder for ingot molds comprising a body portion having ribs on its outer wall, said ribs tapering towards the upper and lower end of the feeder and arranged nearer one end than the other.

11. A reversible feeder for ingot molds comprising a body portion having means on its outer periphery intermediate its ends tapering towards the upper and lower end of the body portion.

12. A reversible feeder for ingot molds, comprising a body portion with the two ends of relative same thickness and having a section intermediate with faces beveled towards said ends.

In testimony whereof we affix our signatures.

BLOOMFIELD H. HOWARD.
ERNEST J. TURNER.
